Primary Examiner — Joseph Kukella*Assistant Examiner* — Heather Ann Laaveg Wencl(74) *Attorney, Agent, or Firm* — BakerHostetler(57) **CLAIM**

The ornamental design for a safety belt retractor, as shown and described.

DESCRIPTION

FIG. 1 is a top, front perspective view of a safety belt retractor;

FIG. 2 is a bottom, rear perspective view thereof;

FIG. 3 is a side, front perspective view thereof;

FIG. 4 is a side, rear perspective view thereof;

FIG. 5 is a top end view thereof;

FIG. 6 is a front end view thereof;

FIG. 7 is a rear end view thereof;

FIG. 8 is a bottom end view thereof;

FIG. 9 is a left side view thereof; and,

FIG. 10 is a right side view thereof.

The dot-dot broken lines are for the purpose of illustrating boundaries that form no part of the claimed design. The dot-dash broken lines are for the purpose of illustrating environmental structure and form no part of the claimed design.

1 Claim, 5 Drawing Sheets(56)
